UNITED STATES PATENT OFFICE.

ARTHUR W. BROWNE, OF PRINCE'S BAY, NEW YORK, ASSIGNOR TO THE
S. S. WHITE DENTAL MANUFACTURING COMPANY, OF PHILADELPHIA,
PENNSYLVANIA.

DESIGN FOR A TREADLE.

SPECIFICATION forming part of Design No. 24,934, dated November 26, 1895.

Application filed October 5, 1895. Serial No. 564,808. Term of patent 14 years.

To all whom it may concern:

Be it known that I, ARTHUR W. BROWNE, of Prince's Bay, in the county of Richmond and State of New York, have invented a new and original Design for Treadles, of which the following is a specification, reference being had to the accompanying drawing, which shows a view in perspective of my design.

The leading feature of my design is a lug or short arm at the toe of the treadle and extending forwardly therefrom.

A is the treadle, of a general outline substantially that of the human foot and having

the slotted and perforated toe B with the forwardly-projecting lug or short arm C, having 15 a hole *a* through it near its outer end.

I claim as my invention—

The design for a treadle, substantially as shown and described.

In testimony whereof I affix my signature 20 in presence of two witnesses.

ARTHUR W. BROWNE.
